DESIGN FOR A WINDSHIELD WIPER ARM

Fred A. Krohm, Gary, Ind., assignor to Productive Inventions, Inc., a corporation of Indiana

Application May 13, 1947, Serial No. 139,011

Term of patent 14 years

(Cl. D14—6)

To all whom it may concern:

Be it known that I, Fred A. Krohm, a citizen of the United States, and a resident of Gary, in the county of Lake and State of Indiana, have invented a new, original, and ornamental Design for a Windshield Wiper Arm, of which the following is a specification, reference being made to the accompanying drawing, forming a part thereof.

Figure 1 is a top plan view of a windshield wiper arm, showing my new design;

Figure 2 is a side view in elevation of the wiper arm illustrated in Figure 1; and

Figures 3 through 5 are sectional views taken substantially on lines 3—3, 4—4, and 5—5 of Figure 2, respectively.

The dotted lines shown in Figures 1 and 2 are for illustrative purposes only.

I claim:

The ornamental design for a windshield wiper arm, substantially as shown and described.

FRED A. KROHM.
